UNITED STATES PATENT OFFICE.

THEODORE F. MORSE, OF SILVERCREEK, NEW YORK, ASSIGNOR TO HUNTER-LEY MANUFACTURING COMPANY, OF SILVERCREEK, NEW YORK, A CORPORATION OF NEW YORK.

LUBRICATOR.

No. 807,848.

Specification of Letters Patent.

Patented Dec. 19, 1905.

Application filed April 6, 1905. Serial No. 254,136.

To all whom it may concern:

Be it known that I, THEODORE F. MORSE, a citizen of the United States, residing at Silvercreek, in the county of Chautauqua and State 5 of New York, have invented a new and useful Improvement in Lubricators, of which the following is a specification.

This invention relates to that class of automatic journal or bearing lubricators comprising a reservoir or casing which incloses the bearing, a centrifugal disk mounted on the shaft or other part to be lubricated and dipping with its lower portion into the oil in the reservoir, and a stationary feed device which receives the oil thrown off by the disk and delivers the same to the shaft-bearing.

The object of my invention is to improve the construction of the stationary oil-feed device with a view of insuring a constant and positive feed of the oil to the bearing.

In the accompanying drawings, Figure 1 is a sectional elevation of a double eccentric or crank shaft and a pair of pitmen provided with the improvement. Fig. 2 is a transverse vertical section in line 2 2, Fig. 1. Fig. 3 is a horizontal section in line 3 3, Fig. 2.

Similar letters of reference indicate corresponding parts throughout the several views.

A indicates a shaft, supported in a standard 30 A' and having double eccentrics or cranks *aa*, and B B are pitmen having heads or bearings C of any ordinary construction which embrace the eccentrics or cranks *a*.

D is the oil reservoir or casing inclosing 35 the pitmen-heads and cranks and closed on all sides except where the same has openings for the passage of the pitmen.

E indicates the centrifugal member, preferably consisting of a dished disk secured to 40 the shaft between the pitmen-heads and dipping into the oil in the lower portion of the reservoir, so as to transfer a portion of the oil from the latter to the stationary feed member F. This feed member consists of a plate 45 or fin arranged transversely in the reservoir and depending from the closed top thereof, the plate extending across both pitmen-heads in line with their oil-holes *g*, as shown. The

lower edge of the feed-plate is notched or recessed to receive the peripheral portion of the 50 disk, as shown at *f*. The portions of the plate on opposite sides of the disk are V-shaped, and their points or apexes *f'* coincide with the oil-holes *g*. By this construction the plate is provided above each pitman-head with inclined edges *f'' f''*, which converge to the drip-points *f'*, located directly over the corresponding oil-holes, causing the oil which is thrown against the feed-plate by the centrifugal disk to flow down the side of the plate 60 and then follow its inclined edges to said points, from which it falls in drops or small quantities into said oil-holes.

The V-shaped portions of the feed-plate 65 preferably extend to within a short distance of the upper sides of the pitman-heads; and the rotary disk is of sufficient diameter to extend nearly to the top of the oil-reservoir.

In the drawings the invention is shown in connection with two oppositely-acting pitmen, such as are employed in grain-separators for vibrating screens in opposite directions; but the improvement is equally applicable to a single pitman-head, journal, or other part to be lubricated.

70 I claim as my invention—

The combination of a shaft having a pair of eccentrics, pitmen-heads embracing the eccentrics and having oil-holes, a centrifugal transfer member mounted on the shaft between said heads, and a transverse feed-plate depending from the upper side of the reservoir and provided in its lower edge with a central recess which receives the periphery of 80 said member and on opposite sides of the member with V-shaped portions having their apexes arranged directly over the oil-holes of the pitmen-heads, the opposing inner edges of said V-shaped portions forming the sides 85 of said recess, substantially as set forth.

90 Witness my hand this 4th day of April, 1905.

THEODORE F. MORSE.
